UNITED STATES PATENT OFFICE

170,678

COMBINED WATER COOLER AND FAN

Benjamin Cisenfeld, Baltimore, Md.

Application February 12, 1953, Serial No. 23,589

Term of patent 7 years

(Cl. D67—4)

To all whom it may concern:

Be it known that I, Benjamin Cisenfeld, a citizen of the United States, residing at Baltimore, State of Maryland, have invented a new, original, and ornamental Design for a Combined Water Cooler and Fan, of which the following is a specification, reference being had to the accompanying drawing, forming a part hereof.

Fig. 1 is a front elevational view of the combined water cooler and fan, showing my new design;

Fig. 2 is a side elevational view; and

Fig. 3 is a rear elevational view, thereof.

I claim:

The ornamental design for a combined water cooler and fan, as shown,

BENJAMIN CISENFELD.
